UNITED STATES PATENT OFFICE.

HENRY SWALLEY, OF MILWAUKEE, WISCONSIN.

DESIGN FOR A SKELETON FRAME FOR ENTRY-SHEETS.

SPECIFICATION forming part of Design No. 31,392, dated August 15, 1899.

Application filed July 22, 1899. Serial No. 724,869. Term of patent 7 years.

To all whom it may concern:

Be it known that I, HENRY SWALLEY, a citizen of the United States, residing at Milwaukee, in the county of Milwaukee and State of Wisconsin, have invented and produced a new and original Design for a Skeleton Frame for Entry-Sheets; and I do hereby declare the following to be a full, clear, and exact description of the same, reference being had to the accompanying drawings, forming a part thereof.

In the said drawings, Figure 1 is a plan view, Fig. 2 a vertical sectional view on the line 2 2 of Fig. 1, and Fig. 3 a horizontal sectional view on the line 3 3 of Fig. 1, of a skeleton frame for entry-sheets embodying my new design.

My design relates to the new and original shape or configuration of the article.

The leading or essential feature consists in the unitary design for a skeleton frame for entry-sheets made the subject of illustration, comprising the generally-rectangular shape of said frame having vertical and horizontal cross-pieces, whereby series of rectangular openings are formed within the said frame.

A A represent the vertical outer side edges, B the horizontal top edge, and C the horizontal bottom edge, of the said frame.

D represents an inner edge forming the boundary of the left-hand series of openings, said edge D being raised above the plane of the outer edges A A B C and to the same plane as that of the beads A' A' B' C', which are formed just inside the outer edges A A B C of said frame.

E designates a horizontal cross-piece extending from one bead A' to the opposite bead

A' in the form of a bead rising from the plane of the edges A A to the plane of the beads A' A', and F F designate panels between the left-hand bead A' and the inner edge D and between the bead B', cross-piece E, and bead C', the said panels being of the same plane as that of the adjacent outer edge A.

G represents the vertical cross-piece in the form of a bead rising from the plane of the top and bottom edges B C to the plane of the beads B' C'. The described inner edge D, vertical cross-piece G, and right-hand bead A' are cut away at one end, as indicated at d, g, and a', respectively, so that the openings between said parts D, G, and A' are of greater width at these points than elsewhere.

Minor features of said design include the shape of the inturned edges of the top edge B, as shown at H, of the bottom edge C, as shown at I, and of the right-hand edge A, as shown at J, the said inturned edges being flat and parallel with the plane of said edges B, A, and C; also, the shape of the upper and lower right-hand corners of the frame, which are formed on oblique lines, as shown at K K.

Having thus described my invention, what I claim as new, and desire to secure by Letters Patent, is—

The design for a skeleton frame for entry-sheets, substantially as shown and described.

In testimony whereof I affix my signature in presence of two witnesses.

HENRY SWALLEY.
